UNITED STATES PATENT OFFICE.

JULES R. AUBERSON, OF PROVIDENCE, RHODE ISLAND.

DESIGN FOR A BADGE.

SPECIFICATION forming part of Design No. 24,769, dated October 22, 1895.

Application filed August 31, 1895. Serial No. 561,155. Term of patent 3½ years.

To all whom it may concern:

Be it known that I, JULES R. AUBERSON, a citizen of France, residing at Providence, in the State of Rhode Island, have invented and produced a new and original Design for a Badge; and I do hereby declare the following to be a full, clear, and exact description thereof, reference being had to the accompanying drawing, and to the letters of reference marked thereon, which forms a part of this specification.

This design is intended to be applied to an article of jewelry or ornament and worn as a badge.

The figure of the drawing is a face view of a badge embracing my new design, and is deemed sufficient to fully illustrate the same.

The leading feature of my design consists in the representation within a border of one

side of a silver dollar, a representation of an eagle, with divergent rays or bands extending above the eagle, and having panels intermediate of the represented eagle and the dollar for containing any suitable words.

In the said drawing, *a* represents the silver dollar; *c*, the eagle; *e e*, the divergent rays or bands extending above the eagle, and *ffff* panels.

What I claim as new is—

The design for a badge, as herein shown and described.

In testimony that I claim the foregoing I have hereunto set my hand this 6th day of August, 1895.

JULES R. AUBERSON.
